UNITED STATES PATENT OFFICE

2,537,486

AUTOMATIC GATE

Henry W. Stevens, Gulfport, Miss.

Application October 18, 1949, Serial No. 122,040

1 Claim. (Cl. 39—45)

1

This invention relates to new and useful improvements in structural refinements in automatic gates, more particularly fence gates, and the principal object of the invention is to facilitate opening and closing of the gate in response to the passage of a vehicle through the doorway.

This object is achieved by the provision of a vertically slidable closure in the doorway, together with normally inclined approaches disposed at opposite sides of the closure, together with means for operatively connecting the approaches to the closure so that the latter is slid to its open position when the approaches are depressed by the passage of a vehicle over the same.

Some of the advantages of the invention lie in its simplicity of construction, in its convenient and efficient operation, and in its adaptability to installation in doorways of different sizes and types.

With the above more important objects and features in view and such other objects and features as may become apparent as this specification proceeds, the invention consists essentially of the arrangement and construction of parts as illustrated in the accompanying drawings, in which:

Figure 1 is a front elevational view of the invention;

Figure 2 is a cross sectional view, taken substantially in the plane of the line 2—2 in Figure 1;

Figure 3 is a cross sectional view, taken substantially in the plane of the line 3—3 in Figure 2;

Figure 4 is a fragmentary cross sectional detail, taken substantially in the plane of the line 4—4 in Figure 3;

Figure 5 is a cross sectional detail, taken substantially in the plane of the line 5—5 in Figure 3;

Figure 6 is a cross sectional view, similar to that shown in Figure 2, but illustrating the closure in a partially raised position; and,

Figure 7 is a cross sectional view, similar to that shown in Figure 2, but on a reduced scale, and illustrating the gate in its open position.

Like characters of reference are employed to designate like parts in the specification and throughout the several views.

Referring now to the accompanying drawings in detail, the invention consists of an automatic gate designated generally by the reference character 10, the same embodying in its construction a pair of spaced uprights 12 connected together at their upper ends by a transverse mem-

ber 14 and defining between them a gateway or a doorway, as will be clearly apparent.

As is best shown in Figure 4, the uprights 12 are preferably channel-shaped and have open opposing sides and it is to be noted that a parting strip 16 extends longitudinally in each upright so as to provide a set of tracks or guides 18, 20.

A closure member designated generally by the reference character 22 constitutes the gate proper and laterally projecting portions 24 thereof are vertically slidable in the guides 18 of the two uprights 12.

A movable cross member in the form of a shaft 26 has the ends thereof slideable in vertical slots 28 provided in lower end portions of the uprights 12 and suitable anti-friction bearings 30 are mounted adjacent the ends of the shaft 26, these bearings being movable vertically in the tracks

20 of the two uprights 12 and it being understood that the diameter of the bearings is slightly less than the width of the tracks 20, while the diameter of the shaft 26 is slightly less than the width of the slots 28, so that the shaft 26 may move laterally to a slight extent as well as slide in a vertical direction.

Pairs of inclined approaches 32 are provided at the opposite sides of the closure 22 and are equipped at the relatively high ends thereof with pairs of hook-shaped ears 34, whereby the approaches are pivotally mounted on the shaft 26. The ears 34 of the approaches at one side of the closure 22 extend through the closure, as illustrated at 36 in Figure 4.

The relatively low ends of the approaches 32 are movable horizontally on the ground, to which end they may be equipped with suitable rollers 38, as illustrated in Figure 2.

The operative connection between the approaches 32 and the closure 22 assumes the form of a pair of winch units 38 which are mounted at the upper ends of the uprights 12, each winch unit including a rotatable shaft 40, carrying a relatively small drum 42 and a relatively large drum 44 (see Figure 5).

A cable 46 is windable in one direction on the drum 42 while a cable 48 is windable in a relatively opposite direction on the drum 44, the cables 46 of the two winch units being anchored to the end portions of the shaft 26 as indicated at 50, while the cables 48 are anchored to the projecting portions 24 of the closure 22 as indicated at 52.

It will be apparent from the foregoing that by virtue of the vertical slidability of the shaft 26

and the horizontal slidability of the rollers 38, the approaches 32 are depressable from their inclined positions to a substantially horizontal position as shown in Figure 7, this being effected by the weight of a vehicle passing over them. Accordingly, when the invention is placed in use and the vehicle approaches the gate, the members 32 are depressed and the cables 46 are unwound from the drums 42, thus rotating the drums 44 and causing the cables 48 to wind on the latter; so as to slide the closure member 22 upwardly to its open position. Needless to say, the closure member remains open until the vehicle leaves the approaches at the opposite side of the gate, and it is to be noted that by virtue of the relatively small drums 42 and relatively large drums 44, comparatively small amount of depressing movement of the approaches will be sufficient to raise the closure member to a substantial height.

After the vehicle leaves the approaches, the closure member 22 descends to its lowered position and the approaches are automatically elevated by the effect of gravity on the closure member, which member is heavier than the approaches themselves.

The side play of the shaft 26 in the slots 28 and the side play of the bearings 30 and the tracks 20 permit the shaft 26 to shift itself in the direction of travel of the vehicle, such as for example, if a vehicle travels in the direction of the arrow 54 in Figure 4, the shaft 26 is shifted in the same direction and the bearings 30 roll along the parting strips 16 and are spaced from the flanges 56 of the uprights 12. On the other hand, when the vehicle travels in a direction opposite to that shown at 54, the bearings 30 roll along the flanges 56 and are spaced from the parting strips 16.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to

without departure from the spirit and scope of the invention as claimed.

Having described the invention, what is claimed as new is:

In a vehicle operated gate, the combination of a pair of channel-shaped spaced uprights defining a doorway therebetween, parting strips secured to the base of the channel and dividing the channels into sets of guides, a doorway closure slidable vertically in one set of said guides, a cross-member extending between said uprights and being in the form of a shaft, freely rotatable bearing means associated with the end portions of said shaft and engageable for vertical rolling movement within said second set of guides, inclined approaches disposed at opposite sides of said closure and having their relatively high ends pivotally mounted on said cross member, the relatively low ends of said approaches being slidable horizontally on the ground whereby the approaches may be depressed to a substantially horizontal position by the weight of a vehicle thereon, a winch mechanism mounted on the upper portion of one of said uprights and including a pair of simultaneously rotatable drums of different diameters and a pair of cables windable in relatively opposite directions on the respective drums, the cable associated with the relatively large drum being connected to said closure and the cable associated with the relatively small drum being connected to said cross member, whereby said closure may be slid to an open position by the depression of said approaches.

HENRY W. STEVENS.
